CLAIM

The ornamental design for a monitor stand, as shown and described.

DESCRIPTION

FIG. 1 is a front, right and top perspective view of a monitor stand, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof; and,

FIG. 9 is another front, right, and top perspective view of the monitor stand of FIG. 1, wherein the monitor stand is in a folded state.

The broken lines shown in the drawings are included for the purpose of illustrating portions of the monitor stand that form no part of the claimed design.
